UNITED STATES PATENT OFFICE.

COLIN CAMPBELL, OF RUTHERFORD, NEW JERSEY.

STEAM-BOILER.

1,211,912.

Specification of Letters Patent.

Patented Jan. 9, 1917.

Application filed April 16, 1915. Serial No. 21,812.

To all whom it may concern:

Be it known that I, COLIN CAMPBELL, a citizen of the United States, residing at Rutherford, in the county of Bergen and 5 State of New Jersey, have invented certain new and useful Improvements in Steam-Boilers, of which the following, taken in connection with the accompanying sheet of drawings, is a full, clear, and concise de- 10 scription thereof.

My present invention relates to certain improvements in the construction of steam boilers and, among the objects of the invention, are to provide a flame or baffle-wall 15 adjacent the fire-box of such construction as will effectually withstand the high temperatures encountered and outlast, even under overload conditions, baffle-walls as now commonly constructed.

20 A further object of my invention is to provide, in connection with baffle-walls and boiler-tubes, as heretofore used, a clamping device of such construction that when co-operatively associated with the tubes and 25 walls, they will add support to, and strengthen, the latter as well as prevent leakage of combustible gases therethrough and around the boiler tubes. This clamping device is designed to act as a substitute for 30 the supporting or strengthening cross-beams, or what are commonly known as "flame-bars" extending between the adjacent rows of tubes and across the apparatus for the purpose of adding rigidity and support 35 to the baffle-wall. My improved clamp is of such novel construction that it may be expediently applied to the tubes, notwithstanding the limited operating space that 40 ordinarily exists between the individual tubes.

A further object of my invention is to provide, in a new and novel manner, means for introducing an increment of atmospheric air to the gases of combustion, as 45 difficulties often arise in drawing the proper amount of air through the fuel bed, owing to irregularities in the thickness of the fire, or resistance to the passage therethrough, on account of ashes, clinkers, etc., which 50 prevents the full heat value of the fuel being developed. By means of my invention this auxiliary air inlet introduces the air at a point where it will be caused to co-mingle with the volume of passing gas before it 55 has passed through, what is commonly referred to as the "second pass" of the ap-

paratus. In addition to serving as an auxiliary air inlet, this feature of my invention also serves the function of a strengthening cross-beam, in lieu of the ordinary L-beam now commonly employed. One advantage of combining the cross-beam and the auxiliary air inlet in the manner I propose, is to lengthen the life of said beam owing to the fact that the cool incoming air counteracts the destructive tendency of the high temperatures of the combustible gases. In this way the metal does not deteriorate with the same rapidity as heretofore.

Finally, according to another phase of my invention, I associate with the auxiliary air inlet passage a steam injector, the nozzle of which is so positioned as to direct a stream of steam longitudinally therethrough so that said steam may serve as a vehicle to 70 propel the air into the combustion chamber.

Referring to the accompanying drawings, Figure 1 illustrates a conventional form of steam boiler embodying my invention, one side wall being broken away to show the interior structural arrangement of the parts. Fig. 2 is a fragmentary detail, partly in cross section, on an enlarged scale, showing my improved construction of flame or baffle-wall, repair clamp and combined cross-beam and auxiliary air inlet. Fig. 3 is a view similar to Fig. 2 showing a modification and omitting the cross-beam. Fig. 4 is a view in cross section showing one end of the hollow auxiliary air inlet-beam and a steam injector. Fig. 5 is a detail view showing the conventional form of fire brick, the individual bricks of which are separated from each other by a layer of high temperature cement, a feature which accords with one phase of my invention. Fig. 6 is a plan view of my repair clamp in clamping position. Fig. 7 is a perspective view in open position. Fig. 8 is a view in side elevation of a modification thereof. Fig. 9 is a fragmentary detail of the rear metal baffle plates, in front plan, showing the series of angularly-disposed boiler tubes in section and illustrating the manner in which leakage of gases occur in the present known construction when the brick-work facing becomes defective, or breaks down.

In the conventional form of steam boiler illustrated the gases of combustion rise from the fire and pass around the device in the manner indicated by the arrows, passing

first through the forward portion, then over the top of the flame or baffle-wall 1, and then downwardly through the central or what is commonly referred to as the "second pass", the gases being directed and caused to flow in this direction by the hanging bridge-wall 2 and the second baffle 3, thence through the rear portion of the apparatus, from whence it is led to the stack or flue through the rear wall.

The flame, or baffle-wall, as commonly constructed, comprises a pair of metal plates through which the tubes project, these being reinforced on the fire side by a layer of fire brick of the conventional form shown in Fig. 5. Where a vertical baffle-wall is used, and the tube is disposed at an angle, as shown specifically in Fig. 9, there exists between the orifice of the baffle-plate and the tube, clearances or spaces, 3^a, which would permit the passage of the gases if it were not for the adjacent layer of fire brick. Frequently, however, owing to the high temperature of the combustible gases, the brick work deteriorates, disintegrates or otherwise becomes defective, causing a leakage through the wall and around the tubes. When such openings occur the combustible gases flow through the wall into the second pass without contacting with all of the tubes in the first pass. This passing of the gases also results in a destruction of the iron-work, as well as causing the gases to be directed toward and impinge on the second flame-wall or bridge, thus tending to destroy it, and when such gases penetrate the second baffle, or flame-wall, they are caused to pass direct to the stack without impinging or contacting with all of the tubes in each pass, as intended. Thus, the boiler efficiency is very greatly reduced. In order to overcome these objectionable characteristics of the present known construction, I have devised the clamping device illustrated in detail in Figs. 6 to 8 inclusive. This clamping device is designed to coöperate with and surround the boiler tube and abut against the rear metal plate of the baffle-wall, as is shown in Figs. 1, 2 and 3. The clamp comprises essentially two semi-annular parts 4 and 5, the same being hinged at one end by the slotted tongue and hook arrangement shown at 6. The semi-annular parts, 4 and 5, are provided with outwardly-extending flanges 7, which abut against the rear plate of the baffle-wall and serve to cover any space or opening that may exist or may occur between the boiler tube and the plate by reason of the relative contraction or expansion of metals, or by reason of loose fit, or otherwise. Therefore, should the brickwork become defective, the combustible gases will be prevented from penetrating the baffle-wall and will be caused to flow their intended course around all of the tubes and thus produce maximum

efficiency. The two-part clamp is provided with a tightening bolt 8 through the instrumentality of which an absolutely tight connection may be obtained when the clamp has been applied to a tube.

The clamping bolt 8 passes through corresponding openings formed in wings 5^a at the ends of the clamp sections 4 and 5, the threaded end of the bolt engaging a nut having an angular portion which is received within and interlocks with a correspondingly shaped counter-sunk end 8^a of one of the bolt receiving openings. The nut is thus locked against relative rotation so that the bolt can be readily tightened or loosened by applying a suitable tool to the polygonal head thereof. This construction admits of the baffle clamps or collars being easily handled and readily applied to the tubes, even in the very limited space which is provided between the tubes.

In cases where the flame or baffle-wall 1 is perpendicularly positioned and the tubes are positioned at an angle thereto, I form the clamping device as shown in Fig. 8, in which the wall-abutting flange 7 is vertical, while the tube-receiving bore or opening of the clamp is angularly disposed thereto, as is shown clearly in this illustration. By using a clamp of the described construction the desired repair may be made cheaply and expeditiously. By hinging the two parts, as proposed, the clamp may be applied to a tube conveniently notwithstanding the limited space which is available to operate in.

A clamping device of the construction illustrated has great gripping and holding power, and the more the bolt 8 is tightened, the greater will be the bite of the clamp parts upon the tubes, and thus a very rigid connection between the tube and the clamp is obtained which adds greatly to the ability of the clamp to support the baffle or flame bridge.

According to another phase of my invention, I construct the baffle or flame-wall 1 in such a manner as will effectually withstand the high temperatures of the gases of combustion and prevent leakage around the tubes and through the wall. I do this by interposing between the individual brick, of which the wall is partly constructed, a layer of refractory cement 9 that withstands high temperature, and preferably add an additional layer of brick 10 to the wall with a layer of high temperature cement 11 separating the adjacent brick layers, as shown in detail in Fig. 2. I find by actual practice that a wall so constructed is very durable and will outlast any flame-wall that has been used in the past of which I have knowledge. I may, instead of using two or more layers of brick, use a single layer with a layer of high temperature cement 11 interposed between it and the metal plate 12 of

the wall, as shown in Fig. 3. Such a construction possesses advantages which are not obtained by walls of present known construction.

5 According to another phase of my invention, I substitute for the usual L-beam extending across the bank of tubes at the top of the flame-wall and which is supported by the side walls of the apparatus, a rectangular hollow beam 13 and utilize the same as an air intake for the admission of atmospheric air to the interior of the apparatus for increasing the combustion of the gases. This beam is provided with a suitable air 10 inlet 14 opened to the atmosphere and suitable outlets 15 opening from the hollow passage 16 into the combustion chamber. I also provide a steam injector 17 at the entrance to the hollow beam for the purpose 15 of propelling the air inwardly. It is manifest that the incoming cool air has a tendency to maintain the cross-beam 13 at a much lower degree of temperature than it otherwise would be if it simply contacted 20 with the high temperature gases. Thus, the life of the beam of my improved construction is much greater than the usual form of L-beam heretofore used. In addition to this, the added increment of oxygen to the 25 gases is made at a most desirable point, to wit: where it will co-mingle with all of the gases as they flow to the "second pass."

While I have disclosed in the accompanying drawings preferable embodiments of the 30 features of my invention, I do so by way of example only, having it understood that

I do not limit myself to the specific structural characteristics disclosed, as the same may be varied without departing from my invention as defined by the appended 40 claims.

Having thus described my invention, what I claim as new herein and desire to secure by Letters Patent is:—

1. The combination with a flame wall and 45 boiler tube, of a baffle collar formed in sections, each section including a flange adapted to fit against the flame wall and a flange adapted to fit against the tube, and the tube engaging flanges cooperating with each 50 other to form a bore disposed at an angle to the plane of the flame wall engaging flanges, and means for locking the sections in operative position.

2. The combination with a flame wall and 55 boiler tube, of a baffle collar formed in complementary sections, each section including a flame wall engaging flange and a boiler tube engaging flange, the complementary sections being provided at one end thereof with 60 corresponding ears having bolt receiving openings therein and having a detachable and interlocking hinged connection at the opposite ends thereof, a clamping bolt passing through the bolt receiving openings of 65 the ears, and a nut engaging the threaded end of the bolt and constructed to interlock with one of the ears so as to be held against rotation.

In witness whereof I have hereunto set 70 my hand.

COLIN CAMPBELL.

Copies of this patent may be obtained for five cents each, by addressing the "Commissioner of Patents, Washington, D. C."
